UNITED STATES PATENT OFFICE.

CLIFFORD SHATALROE, OF INDIANAPOLIS, INDIANA.

FLYCATCHER.

1,270,222.

Specification of Letters Patent. Patented June 18, 1918.

Application filed September 28, 1917. Serial No. 193,783.

To all whom it may concern:

Be it known that I, CLIFFORD SHATALROE, a citizen of the United States, residing at Indianapolis, in the county of Marion and State of Indiana, have invented new and useful Improvements in Flycatchers, of which the following is a specification.

This invention relates to a fly catcher, and the object is to provide a frame for holding 10 a sheet of adhesive fly paper, and designed to be used for catching flies by a sweep of the hand when the device is grasped in the manner in which a fan is held. The article may be employed where flies assemble 15 in considerable numbers, and is also suitable for general use.

In the drawings:

Figure 1 is a top plan view of the device.

Fig. 2 is a perspective view of the wire 20 frame for holding the paper.

The frame comprising the main portion of the device may, if so desired, be formed of a single piece of wire bent into suitable form for providing a handle portion and a 25 plurality of wing portions, the latter being adapted to engage and support the adhesive fly paper. The handle is designated 10 and may comprise a plurality of lengths of wire crossing each other or twisted together at 30 12, and portions extending lengthwise with reference to the handle 10, the wire being bent at a sharp angle at the points 14 and being deflected in the direction shown for forming arms or members 15, which latter 35 are deflected and form an engaging device 16, the latter projecting at an angle with the plane of the wings. The continuous wire member is again deflected to form side por-

tions 17 extending to angular portions 18, where the wire is again deflected and crosses 40 member 15, the extreme end forming a barb or engaging device 20, extending in a direction opposite to members 16, and designed to engage the adhesive fly paper from the 45 opposite side.

The sheet of adhesive material is passed between the wing members, so that members 19 will contact with one surface of the paper and members 17 with the other surface thereof. The paper is then engaged by por- 50 tions 16, 18 and 20 of each wing, and is securely held in position when the device is subjected to somewhat rough usage.

What is claimed is:

In a device of the class described, a han- 55 dle portion of wire or the like including a plurality of prongs the ends of which are bent to form wings for supporting a sheet of adhesive paper, the prongs being first deflected at an angle with each other and 60 in opposite directions, then deflected upwardly from the plane of the wings proper, then deflected longitudinally with refer- 65 ence to the prongs, and finally deflected at an acute angle with reference to said prongs, 70 and to a point adjacent the shank portions of the prongs, and barbs carried by the ends of said deflected members and projecting in a direction opposite to the aforesaid up- 75 wardly turned portions, whereby a sheet of paper is engaged on opposite edges and on both sides by the deflected elements and is retained against movement in all directions.

In testimony whereof I affix my signature.

CLIFFORD SHATALROE.
